UNITED STATES PATENT OFFICE.

FREDERIC S. KOCHENDORFER, OF RIVER FOREST, AND HELMER J. BOE, OF CHICAGO, ILLINOIS, ASSIGNEES TO WESTERN ELECTRIC COMPANY, INCORPORATED, OF NEW YORK, N. Y., A CORPORATION OF NEW YORK.

MECHANISM FOR TREATING CABLES AND STRANDS.

Original application filed December 7, 1921, Serial No. 520,712. Divided and this application filed February 7, 1922. Serial No. 534,806.

This invention relates to mechanism for treating cables and strands, and more particularly to an air wiping or cleansing mechanism for removing the surplus treating material from the surface of the treated cable or strand.

The object of the invention is to provide a mechanism whereby a smooth, even coating of uniform character will be given to a strand or cable drawn from a treating bath.

This application is a division of Patent 1,526,071 issued February 10, 1925.

The preferred embodiment of the invention comprises a wiping mechanism which directs a blast of air or other suitable medium against the surface of the coated article to remove all surface coating material therefrom as it is drawn from the treating bath.

In the drawings:

Figure 1 is an enlarged fragmentary sectional view of the upper right-hand corner of a paint container showing the surplus paint removing means partially in section mounted therein;

Fig. 2 is an enlarged plan sectional view taken on the line 2-2 of Fig. 1;

Fig. 3 is a fragmentary plan sectional view taken on the line 3-3 of Fig. 2, and

Fig. 4 is a plan section taken on the line 4-4 of Fig. 1.

The air wiping mechanism which forms the subject-matter of the present application has been herein illustrated in connection with a cable or strand handling and working mechanism which forms the subject-matter of our application above identified. The entire machine is fully described in said application, and accordingly a description herein of the machine, aside from the portion thereof which forms the subject-matter of the present application, will be dispensed with, as the same forms no part hereof.

In the drawings, 10 represents the upper right-hand corner of the container holding paint or other treating material through which the cable to be painted is passed. After leaving the paint bath the cable 11 passes through an excess paint removing device 12 which is mounted at the upper right-hand corner of the container and just

below the cover 14 thereof. The device 12 is connected with a compressed air line 15 controlled by a valve 16. Secured to the container is a bracket or support 17 provided with a depression 18 for the reception of the device 12. The surplus paint removing device 12 consists of two sections 21 and 22 hinged at 23 and held closed by a thumb nut and bolt 24. Section 22 is fitted with a stud 25 which passes through the bracket 17 and an opening in the container 12 and is secured to the bracket 17 on the outside of the container by a thumb nut 28. The air line 15 connects with a passage 29 in the bracket 17 which in turn connects with a passage 30 in the section 22. The passage 30 connects with a passage 31 in the section 21 of the device 12. Suitable gaskets 32 are fitted between the sections 21 and 22 and the bracket 17 and the section 22 to prevent any leakage of air where the air passages connect. Formed in the sections 21 and 22 and at right angles to the passages 30 and 31 and connecting therewith are passages 35 and 36. Formed in the contacting surfaces of the sections 21 and 22 for the greater portion of their length are depressions 37 and 38 which together form a passage 40 through the device 12 for the cable 11. In the drawings flat switchboard cable has been shown and the passage 40 formed by the depressions 37 and 38 is of the same cross section, only enlarged so that a suitable space is allowed between the surface of the cable and the wall of the passage 40. If a cable circular in cross section is to be wiped, the passage 40 will be circular to correspond. Connecting the passage 40 formed by the depressions 37 and 38 with the passages 35 and 36 are a plurality of comparatively fine passages 41 formed at such an angle that all are directed at the passing cable (see Fig. 2). As shown in Fig. 3, the passages 41 are also formed at a suitable angle

in a downward direction which acts to wipe the excess paint off the cable which is moving in the opposite direction. The passages 41 will in all cases be formed at an angle which best suits the cable being wiped. Positioned at the top of the surplus paint removing device 12 and suitably secured in an opening formed in the sections 21 and

22 is a polisher 42 within which the cable snugly fits. The passage 40 formed by the depressions 37 and 38 is of such a size that it will take care of a plurality of cables of the same cross sectional shape; the only change required in the device 12 when another size cable is to be operated upon is to change the polisher for one that fits the cable. Positioned above the cover 14 of the 10 container 12 is an auxiliary surplus paint remover 43 comprising a clamping device adapted to clamp burlap 44 or any suitable material around the cable to wipe it a second time before being wound on a 15 reel.

As the cable is drawn from the container 10 blasts of air directed at the surface of the cable wipe from the cable the surplus paint adhering thereto and produces a 20 smooth, even surface.

What is claimed is:

1. In a machine for treating strands or cable, a container holding a liquid bath through which the article is adapted to 25 be drawn, and means adapted to be positioned around the peripheral surface of the article comprising complementary sections each provided with a plurality of air channels adapted to direct air blasts against the 30 peripheral surface of the article and in a direction opposite to that in which the article is moved, one of said sections being movable into and out of an inoperative position with respect to the other.

35 2. A strand working machine, comprising means for coating the strand, separable complementary members having recesses

forming a passage for the strand, and each member provided with a channel for directing a gaseous medium against the strand, 40 and a polisher mounted in said recesses for embracing the strand.

3. In a machine for treating strands or cable, the combination with a container holding a bath of treating material through 45 which the article is adapted to be drawn, of means for removing surplus treating material from the article and comprising a plurality of complementary members, one of which is adapted to be brought into and out of a 50 position wherein it cooperates with the other to form a wall extending around the article, and means for directing a gaseous medium against the article when in the passage 55 formed by said members.

4. In a machine for treating strands or cable, the combination with a container holding a bath of treating material through 60 which the article is adapted to be drawn, of means for removing surplus treating material from the article and comprising a plurality of hinged members, one of which is adapted to be brought into and out of a 65 position wherein it cooperates with the other to form a wall extending around the article, and means for directing a gaseous medium against the article when in the passage formed by said members.

In witness whereof, we hereunto subscribe our names this 30th day of January, A. D., 70 1922.

FREDERIC S. KOCHENDORFER.
HELMER J. BOE.
